US0D1050492S

(12) **United States Design Patent** (10) Patent No.: **US D1,050,492 S**
(45) Date of Patent: ** Nov. 5, 2024

(54) **UNDERWATER BUILDING MATERIAL**

(71) Applicant: **SEASTAINABLE VENTURES, S.L.**,
Barcelona (ES)

(72) Inventors: **Ignasi Ferrer Pellicer**, Barcelona (ES);
Mireia de Mas Romeu, Barcelona (ES);
Anna Lloveras Armengol,
Barcelona (ES)

(**) Term: **15 Years**

(21) Appl. No.: **35/517,091**

(22) Filed: **Mar. 20, 2023**

(80) **Hague Agreement Data**

Int. Filing Date: **Mar. 20, 2023**

Int. Reg. No.: **DM/228538**

Int. Reg. Date: **Mar. 20, 2023**

Int. Reg. Pub. Date: **May 5, 2023**

(51) LOC (14) Cl. **22-06**

(52) U.S. Cl.

USPC **D22/119; D25/48.8**

(58) **Field of Classification Search**

USPC D25/61; D22/119, 121, 199; D30/108,

D30/119, 199

CPC E04B 1/72; E04D 13/004; A01M 29/32;

A01K 61/70; A01K 61/75; A01K 61/73;

Y02A 40/80

See application file for complete search history.

Stabilization of rubble using wire mesh to promote reef recovery, date first available Mar. 8, 2020 [online], [site visited Jan. 29, 2024], Available from the internet URL: bluecornerconservation.org/restoration-news/stabilization-of-rubble-using-wire-mesh-to-promote-reef-recovery (Year: 2020).*

Primary Examiner — Justin M Jonaitis

Assistant Examiner — Jasmine L. Comedy

(57) **CLAIM**

The ornamental design for underwater building material as shown and described.

DESCRIPTION

1.1 : Front

1.2 : Back

1.3 : Perspective

1.4 : Left

1.5 : Right

1.6 : Top

1.7 : Bottom

1.8 : Rear perspective view

The contrast in shading is provided for clarity of illustration only and is not indicative of any contrast in appearance, color, material, or finish, and forms no part of the claimed design.

1 Claim, 8 Drawing Sheets
